UNITED STATES PATENT OFFICE.

DANIEL O'HARA, OF WALTHAM, MASSACHUSETTS.

WATCH-CASE.

SPECIFICATION forming part of Letters Patent No. 340,814, dated April 27, 1886.

Application filed November 24, 1885. Serial No. 183,888. (No model.)

To all whom it may concern:

Be it known that I, DANIEL O'HARA, of Waltham, in the county of Middlesex and State of Massachusetts, have invented certain new and useful Improvements in Watch-Cases, 5 of which the following is a full, clear, and exact description.

This invention relates more particularly, although applicable to watch-cases of other construction, as will hereinafter appear, to watch-cases in which the movement-ring is jointed or hinged within the case center or shell, so as to be capable of being swung into and out thereof, and watch-cases of this character are 15 more particularly known in the trade as "Fitch" watch-cases, and are embraced in Letters Patent of the United States issued to Ezra C. Fitch, dated April 22, 1879, No. 214,642, to which reference is hereby had for a more full description thereof.

This invention consists of a movement-ring which is hinged or jointed within the case center or shell, so as to be capable of being swung into and out thereof, and is provided 25 with a flange overlapping the front side of the case center or shell, and all otherwise substantially as hereinafter described.

In the drawings, all on an enlarged scale, forming a part of this specification, Figure 1 is a central transverse section of a watch-case having a movement-ring jointed or hinged within a case center or shell and provided with a flange overlapping the front side of the case center. Fig. 2 is a face view of the watch-case of Fig. 1 with the crystal and flat bezel-ring detached. Figs. 3 and 4 are transverse sections in detail and at one side of a watch-case, showing a modification, as will herein-after appear.

In the drawings, A represents the case center or shell, formed, as shown, in one seamless piece of a concave shape, open at one side—the front B—and closed at its other side—the back C—and all so as to be suitable to receive a 45 watch-movement carried by a ring, D, which (Figs. 1 and 2) is hinged or jointed at one side, and, as at E, either to the case center or shell A, or (Fig. 3) to a supplemental ring, F, preferably shouldered, as at a, interiorly, for a 50 rest of a corresponding exterior shoulder, b, of the movement-ring D, and also shaped exteriorly with a shoulder, f, to rest upon a cor-

responding shoulder, g, around the inner periphery of the case-center A.

The construction of the case center or shell 55 A above described constitutes no part of this invention, and therefore needs no further description herein, it being deemed sufficient to observe that it is in substance the same as described and shown in the Letters Patent before cited, and to which reference is hereby had for a more particular description thereof. The movement-ring D has a flange, H, surrounding it at its outer portion and in position to overlap the front face of the case-center A or riser 65 G thereat, and this flange preferably is of sufficient width to conceal by its overlap above stated the hinge or joint E of the movement-ring D and the slot J, usually made in the case center or shell to receive the hand-setting lever of the watch-movement, and also the recess or cavity K in the watch-case center, to allow of the insertion of the thumb-nail to swing the watch-movement out of the case-center, turning by the hinge or joint E of the 75 movement-ring upon the case-center. The flange H may be made in one piece with the movement-ring, or in a piece separate therefrom and attached thereto by screws or solder or otherwise, and preferably so as to be, when 80 so attached, practically of one piece therewith. The movement-ring and flange may be of different metals, the flange, as it is exposed, preferably being made of a metal corresponding to the metal of which the exposed portions of 85 the watch-case are made.

In order to allow the movement-ring having a flange, as described, to be swung upon its hinge or joint so as to place it and the watch-movement carried by it in or out of the case 90 center or shell, the case-center or shell and the supplemental ring F, if one is used, is cut out or removed, as at L, back of the hinge or joint.

This invention is to be in no way limited to any particular construction of the hinge or joint of the movement-ring within the case center or shell, nor to any particular construction of the case center or shell, the invention in substance consisting of a movement-ring which is hinged or jointed within the case 95 center or shell, and is provided with a flange for overlapping said shell at its front, substantially as described.

The supplemental ring, shown in Figs. 3 and

4 of the drawings, and which surrounds the movement-ring and has the movement-ring hinged or jointed to it, of itself forms no part of the present invention, it being the subject-
5 matter of a separate application for Letters Patent of even date, and Serial No. 183,983.

Having thus described my invention, what I claim, and desire to secure by Letters Patent, is—

- 10 In a watch-case, the combination of a movement ring or band surrounding and containing the watch-movement and having a flange surrounding it, a case center or shell, and a hinge

or joint covered by the flange of movement-ring and joining same to case-center, which is 15 cut away for the passage of the flange of movement-ring in the swing of said ring on its hinge, substantially as described, for the purpose specified.

In testimony whereof I have hereunto set 20 my hand in the presence of two subscribing witnesses.

DANIEL O'HARA.
